Primary Examiner — Paula Allen Greene*(74) Attorney, Agent, or Firm* — HSMP P.C.(57) **CLAIM**

The ornamental design for a headset for telephone as shown and described.

DESCRIPTION

FIG. 1 is a Top Front Right Side Perspective view of a headset for telephone showing the new design;

FIG. 2 is a Front view thereof;

FIG. 3 is a Rear view thereof;

FIG. 4 is a Left view thereof;

FIG. 5 is a Right view thereof;

FIG. 6 is a Top view thereof; and,

FIG. 7 is a Bottom view thereof.

The broken lines depict portions of the headset for telephone that form no part of the claimed design.

1 Claim, 7 Drawing Sheets(56)
